UNITED STATES PATENT OFFICE.

GILBERT E. PETERSON, OF BISMARCK, NORTH DAKOTA.

WHEEL STRAIGHTENER.

Application filed January 14, 1921, Serial No. 437,327. Renewed June 28, 1922. Serial No. 571,473.

To all whom it may concern:

Be it known that I, GILBERT E. PETERSON, a citizen of the United States, residing at Bismarck, in the county of Burleigh and 5 State of North Dakota, have invented certain new and useful Improvements in Wheel Straighteners, of which the following is a specification, reference being had to the accompanying drawings.

10 This invention relates to wheel straighteners.

An important object of the invention is to provide a device for straightening wheels of the type commonly used upon automobiles 15 and usually designated by the term "artillery". In this type of wheel, a sharp blow at the felly often deforms the hub plate of the wheel. The straightening of these wheels presents peculiar difficulties in that 20 the hub plates must be straightened in addition to the straightening of the rim or the straightening of the rim will not remain permanent, since the deformation of the hub plate permits play of the inner ends of the 25 spokes and results in loosening at the felly.

A further object of the invention is to provide a device for simultaneously straightening the hub plates and returning the felly of the wheel to normal position.

30 A still further object of the invention is to provide a device of this character which is capable of use not only as a wheel straightener but which likewise may be employed for removing wheels from their 35 shafts.

A still further object of the invention is to provide a device of this character which is simple in construction and operation, and the parts of which may be cheaply manufactured.

40 Other objects and advantages of the invention will become apparent throughout the course of the following description:

In the accompanying drawings, wherein 45 for the purpose of illustration is shown a preferred embodiment of my invention, and wherein like reference characters designate like parts throughout:

Figure 1 is a side elevation of a wheel 50 having a wheel straightener constructed in accordance with my invention applied thereto;

Figure 2 is a side elevation partly in section of the straightener applied;

55 Figure 3 is an enlarged sectional view taken through my wheel straightener;

Figure 4 is a detail sectional view showing the mounting of the adjusting and tightening arm,

Figure 5 is a front elevation of the anvil 60 detached, and

Figure 6 is a section on the line 6—6 of Figure 4.

Referring now more particularly to the drawings, the numeral 10 indicates a bar, 65 longitudinally slotted as at 11, the slot extending adjacent one end of the bar. Through the slot at this end of the bar is directed a member 12, preferably circular in cross section and having its upper end screw 70 threaded, as indicated at 13. The lower end of the member 12 is provided with a foot 14 which is turned inwardly beneath the bar 10. The upper threaded end of the member 12 is provided in the diametrically opposed 75 faces thereof with key slots 15.

Slidably mounted upon the side walls of the slot 11 of the bar 10 are blocks 16 which combine to form a rectangular supporting member slidably fitting within the slot and 80 having a central aperture which is circular in form and which is adapted to receive the threaded end of the member 12. Each of the blocks 16 has formed upon its outer face a circular lug 16* which slidably engages in 85 a slot 11* formed in the wall of the slot 11 so that the blocks 16 are pivotally and slidably mounted within the slot 11. Each of the blocks 16 is likewise provided with a key of lug portion 17 which is adapted to extend 90 into the slot 15 of the member 12 and prevent rotation of the member 12. It will be noted that since the members 16 are slidably mounted upon the walls of the slot that the member 12 may be adjusted longitudinally 95 of the bar by sliding these blocks to any desired position. The upper end 13 of the member 12 has mounted thereon a lever nut 18 adapted to engage the upper surface of the blocks 16 to adjust the member 12 100 axially through the same.

Through the slot approximately centrally thereof is directed the reduced upper end 20 of an anvil member 21. The anvil member is preferably provided at the point of 105 reduction with a flange 22 which engages the under surface of the bar 10 and limits the passage of the anvil member 20 therethrough. The lower end of the anvil member 21 is preferably rounded, as at 23, for 110 a purpose presently to appear. The reduced upper end 20 of the anvil member 21, where it

extends through the bar 10, is surrounded by a spring S which is retained in position by means of a washer W suitably secured to the upper end of the reduction 20.

5 The opposite end of the bar 10 from that adjacent which the slot 11 extends is bifurcated to form arms 24, each of which is provided with a longitudinal series of slots adapted to interchangeably receive a pivot 10 pin 25. This pivot pin likewise engages with its ends in pairs of aligned openings 26 formed in the slotted upper end of an arm 27, the aligned openings being arranged in pairs and in series so that the arm 27 may be 15 vertically adjusted upon its respective arm 24 and may be likewise longitudinally adjusted thereon. The lower ends of the arms 27 are each provided with an outturned foot 28 having a hook portion 30 for a purpose 20 presently to appear.

In the use of my device for straightening wheels, the anvil 20 is placed in position upon the hub plate 29 which it is desired to straighten, and the outturned feet 28 of the arms 27 engaged with the felly of the wheel at its point of greatest deformation, the space between the arms 27 preferably being such that they receive therebetween two of the spokes of the wheel. The hooked 25 portions 30 of the feet 28 engage the felly R of the wheel preventing slipping of the feet. The member 12 is then adjusted longitudinally of the slot to bring the inturned foot 14 thereof into engagement with the hub plate upon the opposite side of the wheel and the lever nut 18 tightened. Tightening of the lever nut causes the bar 10 to rock upon the rounded face 23 of the anvil member 20 as a pivot, forcing the felly at its point of 30 engagement by the feet 28 toward the bar 10. At the same time the anvil 20 is bearing upon the plate 29 and tending to straighten the same. If the pressure brought to bear upon the plate 29 does not sufficiently straighten 35 the same, this straightening may be accomplished by striking upon the upper end of the anvil 21 until the plate 29 is straightened. The spring S assists in returning the anvil 21 to its proper position and to prevent slipping of the same upon the bar 10. It will be obvious that by arranging the anvil member 21 against the end of the shaft to 40 which the wheel is secured and by providing a second assembly similar to that employed in connection with the member 12 at the opposite end of the slot, the device may be 45 readily employed as a wheel puller.

From the foregoing it will be obvious that I have constructed a wheel straightener for 50 wheels of the military order which is particularly well adapted for such use and which is simple in construction and in operation; and it will likewise be obvious that the construction of the same as hereinbefore set forth is capable of some change without de-

parting from the spirit of my invention. I, accordingly, do not limit myself to such specific structure as hereinbefore set forth, except as so limited by the subjoined claims.

What I claim is:

1. A device for straightening wheels embodying the usual hub plates, spokes and felly, comprising a bar provided intermediate its ends with an anvil adapted to engage against a hub plate at one side of the wheel and at its ends with members adapted to extend intermediate the spokes of the wheel, one of said members being provided with a foot adapted to engage the hub of the wheel at the opposite side of the hub from so the plate engaged by the anvil and the other of said members being provided with outturned feet adapted to engage the felly. 70

75 15. A device for straightening wheels, comprising a bar provided intermediate its ends with an anvil, a supporting means mounted upon one end of the bar, a member movably mounted on said supporting means and embodying an inturned foot extending beneath the bar, said member being adjustable on 80 the supporting means and on the bar through the medium of said supporting means, and an arm pivotally connected with the opposite end of the bar and embodying an outturned foot. 90

95 20. A device for straightening wheels, comprising a bar provided intermediate its ends with an anvil, an adjustable member, means for mounting said member upon one end of the bar and embodying an inturned foot 100 extending beneath the bar, said member being axially adjustable with respect to said means and an arm pivotally connected with the opposite end of the bar and embodying an outturned foot. 100

105 25. A device for straightening wheels, comprising a bar provided intermediate its ends with an anvil embodying a striking piece, supporting means mounted upon one end of the bar, a member engaged with said supporting means and embodying an inturned foot extending beneath the bar, said member being longitudinally adjustable with respect to said supporting means, said supporting means being adjustable longitudinally of the bar and an arm pivotally connected with the opposite end of the bar and embodying an outturned foot, the pivotal connection between said bar and arm being longitudinally adjustable upon said bar and arm. 110

115 30. A device for straightening wheels, comprising a bar provided intermediate its ends with an anvil, supporting means mounted upon one end of the bar, a member movably supported by said supporting means and embodying an inturned foot extending beneath the bar, said supporting means and member being shiftable simultaneously with respect to the bar, said member being also shiftable 120

125 35. A device for straightening wheels, comprising a bar provided intermediate its ends with an anvil, supporting means mounted upon one end of the bar, a member movably supported by said supporting means and embodying an inturned foot extending beneath the bar, said supporting means and member being shiftable simultaneously with respect to the bar, said member being also shiftable 130

with respect to the supporting means and an arm pivotally connected with the opposite end of the bar and embodying an outturned foot, said outturned foot being provided
5 with a hooked portion adapted to engage the rim of the wheel.

6. A device for straightening wheels, comprising a bar provided intermediate its ends with an anvil adjustable longitudinally
10 thereof, a member mounted upon one end of the bar and embodying an inturned foot extending beneath the bar, said member being mounted for movement longitudinally and laterally of the bar and an arm pivotally
15 connected with the opposite end of the bar and embodying an outturned foot.

7. A device for straightening wheels, comprising a bar provided with a slot extending adjacent one end thereof, the side walls
20 of the slot having slots formed therein,

blocks slidably mounted in the first named slot and each provided with a cylindrical lug adapted to engage one of the slots in the walls of the slot, said slots being provided in their coating faces with openings, a 25 threaded bar directed through the openings of said block and provided in its side walls with grooves, key members formed on said blocks and engaging in said grooves, a foot formed upon the lower end of said member, 30 a lever nut mounted upon the threads thereof and engaging the upper end of said blocks, an anvil mounted within the first named slot of the bar and adjustable longitudinally of the bar within the slot and 35 means at the opposite end of the bar for engaging the felly of the wheel.

In testimony whereof I hereunto affix my signature.

GILBERT E. PETERSON.
